UNITED STATES PATENT OFFICE.

CHARLES W. BOLTON, OF PHILADELPHIA, PENNSYLVANIA.

DESIGN FOR A RUBBER HORSESHOE.

SPECIFICATION forming part of Design No. 35,484, dated December 24, 1901.

Application filed October 29, 1901. Serial No. 80,444. Term of patent 7 years.

To all whom it may concern:

Be it known that I, CHARLES W. BOLTON, a citizen of the United States, residing at Philadelphia, in the county of Philadelphia and State of Pennsylvania, have invented and produced a new and original Design for a Rubber Horseshoe, of which the following is a specification, reference being had to the accompanying drawings, forming part hereof, and in which—

Figure 1 is a perspective view of a rubber horseshoe, illustrating the design of my invention; and Fig. 2 is a central sectional view of the same.

The leading feature of the design consists of the appearance and uniqueness of the rubber horseshoe herein illustrated as a whole.

In the drawings, *a* is the tread, which is of the configuration of a horseshoe. Formed integral therewith and extending upward therefrom on a curve is the flange *c*. Interposed between the tread and flange and formed therewith is a rib *b*. The toe *d* of the

flange tapers to a point, and the quarters *e* extend from this toe in a smooth curve upward and terminate in members *g*, which form the heel.

f is an open space between the members *g* and the tread *a* of the shoe. *h* are lugs extending from the said members.

Rising from the toe *d* to a slight distance above the same and thence extending backward upon either side of the shoe is a band *i*, which comes into alignment with the lugs *h* and is held in place by the adjusting device *j*.

Having described my invention, what I claim as new, and desire to secure by Letters Patent, is—

The design for a rubber horseshoe, substantially as described and shown.

In testimony whereof I have hereunto signed my name.

CHARLES W. BOLTON.
